CLAIM

The ornamental design for an injection molding machine, as shown and described.

DESCRIPTION

FIG. 1 is a front, top and left side perspective view of an injection molding machine showing our new design; FIG. 2 is a rear, top and left side perspective view thereof; FIG. 3 is a front view thereof; FIG. 4 is a rear view thereof; FIG. 5 is a top plan view thereof; FIG. 6 is a right side view thereof; FIG. 7 is a left side view thereof; FIG. 8 is an enlarged view of the portion indicated with the number 8 in FIG. 1; and, FIG. 9 is an enlarged view of the portion indicated with the number 9 in FIG. 2.

The evenly-spaced broken lines illustrating an injection molding machine depict environment and form no part of the claimed design. The dash-dotted broken lines depict the boundary lines of the enlarged detail views and form no part of the claimed design.
